UNITED STATES PATENT OFFICE.

DAVID C. WHEELER, OF BRIDGEPORT, CONNECTICUT, ASSIGNOR TO THE ACME SHEAR COMPANY, OF BRIDGEPORT, CONNECTICUT, A CORPORATION OF CONNECTICUT.

SCISSORS AND SHEARS.

Application filed August 18, 1921. Serial No. 493,362.

To all whom it may concern:

Be it known that I, DAVID C. WHEELER, a citizen of the United States, residing at Bridgeport, county of Fairfield, State of Connecticut, have invented an Improvement 5 in Scissors and Shears, of which the following is a specification.

This invention relates to scissors, shears and the like, and particularly to scissors 10 and shears in which a blade and bow are formed in one piece from a given length of wire of any suitable gauge, and has for an object to provide means for finishing the bows which will improve their appearance 15 and will also increase the strength and stiffness thereof and thus decrease the liability of their getting out of shape in use.

It is a further object of the invention to provide means for strengthening the bows 20 of scissors and shears of this type which will also give them a finished appearance and will decrease the liability of cloth, threads and so forth, becoming caught on the free end of the wire used in forming 25 the bow.

In carrying out my invention I insert between the free end of the wire forming the bow and the shank, a separate member which fills in the space between the two. 30 This filling member is preferably formed with a curved groove at one end to fit the shank and at the other end with a recess or other suitable means to coact with the free end of the bow wire to retain the member in place.

In the accompanying drawings forming part of this specification I have illustrated various ways of carrying out my invention which are merely illustrative as 40 there are numerous other ways in which the desired result may be accomplished.

Fig. 1 is a side elevation of a pair of scissors showing one form with a structure according to my invention applied thereto, 45 a portion of one of the filling members being broken away to show the method of holding the same in position.

Figs. 2 to 10 inclusive are side elevations of a single scissor's handle showing various modifications of the invention.

Fig. 11 is a transverse section substantially on the line 11—11 of Fig. 1.

Fig. 12 is a perspective view of the filling element used in the form shown in Figs. 1 55 and 11.

Referring to Figs. 1, 11 and 12, the shears shown are of the type in which a blade and a handle are formed in one piece from a single length of steel wire of suitable gauge, one end being forged to form the blade 15 60 and the other end bowed to form the handle 16, the two being connected by the shank 17. The two blades and handles are pivoted together by suitable means 18 in the usual manner. Between the free end 19 65 of the bowed handle and the shank 17 is inserted a filling member or element 20 separate from the handle. This element is formed with a groove 21 to fit the shank 17, and in the form shown in Figs. 1, 11 70 and 12, with a recess 22 in its opposite end to receive the free end 19 of the bowed handle. As the material of which the bowed handle is constructed is resilient, the free end 19 is pressed into the recess and 75 the filling member is also pressed against the side of the shank 17, securely retaining the same in position. The edges 23 on the filling member surrounding the groove 21 and the edges 24 surrounding the recess 22 80 are preferably comparatively sharp and the body of the filling member between the two is preferably curved, as shown, to form a substantially continuous surface between the shank and the bowed member adjacent 85 the end thereof.

It will be apparent from an inspection of the drawing that the use of the filling member gives a finished appearance to the scissors handle and also stiffens and 90 strengthens the same as the groove and recess prevent the offsetting of the free end of the bow. It also obviates the necessity of finishing the free end of the bow and, as there is no slot or groove between the free 95 end of the bow and the shank, there is no liability of cloth, thread, and so forth, becoming caught therein in use.

In the modification shown in Fig. 2, the filling member is substantially the same as 100 that shown in Fig. 1 except that the bottom of the recess 25 for the free end of the bow is inclined instead of being parallel with the shank.

In Fig. 3, the end of the bow is rounded 105 at 26 and the recess in the filling member 20 is concaved to fit the rounded end of the bow. This forms a universal connection between the end of the bow and the filling element and allows a slight rocking move- 110

ment between the two to allow a better seating of the filling member on the shank.

Fig. 4 is the reverse of Fig. 3, in that the free end of the bow is concaved at 27 and the outer end of the filling member is rounded at 28 to fit the same.

In the modification shown in Fig. 5, the filling member 20 is recessed, preferably concave, on its outer end at 29 and within 10 this recess between the filling member and the free end of the bow is inserted a second member 30, curved on one side to fit the recess in the filling member and recessed on the other side to receive the free end of the bow. It will be noted that each of the forms shown in Figs. 3, 4 and 5, allow a rocking movement between the free end of the bow and the filling member to allow the said member to seat perfectly on the shank.

20. In the form shown in Fig. 6, a separate element 31 is inserted between the filling member 20 and the free end 19 of the bow which is provided with recesses 32 and 33 on the opposite ends thereof to receive the 25 ends of the filling member 20 and the free end 19 respectively. This member may be provided with suitable ornamentation, as a groove 34, if desired.

30. In Fig. 7, the filling member 20, instead of being formed with plain curves, as shown in Fig. 1, is given a slight ornamentation such as scallops 35 at the edge of the groove 21.

35. In Fig. 8, the filling member is made considerably longer and larger and is adapted to receive a greater amount of ornamentation 36 and may have a bead 37 around the recess for the free end 19.

40. In Fig. 9, the free end 19 is provided with a projection 38 surrounded by a shoulder 39, the projection being adapted to seat in a complementary recess in the filling member 20.

45. In Fig. 10, the connection is the reverse of that shown in Fig. 9, the projection 40 with a surrounding shoulder 41 being formed on the filling member 20 and the projection seating in a recess in the free end 19.

The various modifications described are 50 merely illustrative of my invention and show a number of different ways in which

the filling member may be applied. It will, however, be obvious that numerous other ways may be devised within the scope of my invention for securing the filling element in 55 position.

Having thus set forth the nature of my invention what I claim is:

1. A bowed handle for scissors, shears, and the like, comprising a shank, a free end 60 at one side of the shank, and a separate filling member between the shank and free end, said member and free end being provided with cooperating retaining means.

2. A bowed handle for scissors, shears, 65 and the like, having a shank and a free end adjacent said shank, a separate member between the free end and the shank, and provided with a groove to fit the shank.

3. A bowed handle for scissors, shears, 70 and the like, comprising a shank, a free end adjacent the shank at one side thereof, and a separate member between the free end and the shank provided with a groove to fit the shank and cooperating with the free end to 75 retain the element in place on the shank.

4. A bowed handle for scissors, shears, and the like, comprising a shank, a free end 80 at one side of the shank, and a separate filling member between the shank and free end, said filling member provided with a groove to fit the shank and a recess to receive the free end.

5. A bowed handle for scissors, shears, and the like, comprising a resilient member 85 having a shank and a free end at one side of the shank, and a separate filling member between the shank and free end having a groove to fit the shank and pressed thereagainst by the resiliency of the handle. 90

6. A bowed handle for scissors, shears, and the like, comprising a shank, a free end 95 at one side of the shank, and a separate filling member between the shank and the free end provided with a groove to receive the shank, the filling member and the free end being provided with cooperating means comprising a recess in one of said members adapted to receive a portion of the other member.

In testimony whereof I affix my signature.
DAVID C. WHEELER.
